UNITED STATES PATENT OFFICE

CHARLES I. WALKER, OF LOS ANGELES, CALIFORNIA, ASSIGNOR TO CHICAGO RAILWAY EQUIPMENT COMPANY, OF CHICAGO, ILLINOIS, A CORPORATION OF ILLINOIS

HANGERLESS BRAKE BEAM

Application filed May 14, 1927. Serial No. 191,422.

My invention relates to railway rolling stock and consists in an improved hangerless brake beam structure and its mounting on the car truck.

5 It has been previously recognized that there are advantages in using a brake beam support member extending under the brake beam for the sole support of the brake beam, thereby eliminating the swinging hangers usually employed.

10 The general object of my invention is to provide a support of this nature in which the beam may be properly supported and the friction which naturally results from this 15 type of support may be overcome.

The specific objects of my invention attained by the use of the details of my structure will be apparent from the following description.

20 In the accompanying drawings which illustrate my invention—

Figure 1 is a section taken longitudinally of the truck through one half of the spring plank and the adjacent brake beam and its 25 supporting structure and indicating the adjacent wheel.

Figure 2 is a vertical transverse section taken on line 2—2 of Figure 1.

Figures 3 and 4 correspond to Figures 1 30 and 2 but illustrate a modified form of my invention.

Figures 5 and 6 similarly illustrate another modification of my invention.

Figures 7 and 8 similarly illustrate a third 35 modification of my invention.

In the structure illustrated in Figure 1, one half of the truck spring plank is indicated at 1 and it will be understood that the 40 brake beam illustrated is of the truss type, the compression member being indicated at 2 and the tension member indicated at 3. A cross piece 4 braces the tension and compression members of the beam and may constitute the strut at the middle of the beam or may 45 take the form of an additional brace between the strut and the end of the beam, in which case it will be understood that this cross piece 4 will be duplicated on opposite sides of the strut.

50 A brake beam support is indicated at 5 in

the form of an upwardly facing channel secured to the spring plank by means of rivets 6 passing through suitable bushings 7. The cross piece 4 has a bracket 8 riveted thereto and this bracket extends downwardly and 55 may be provided with one or more seats 9 for receiving an anti-friction bearing element such as the ball bearing 10. Bracket 8 is also provided with depending lugs 11 which are provided with bearings for a journal 12 on 60 which is mounted a roller 13; the journal and roller being located below the bottom of support arm 5 and the roller engaging the track formed by the bottom of arm 5. The channel formed by arm 5 forms a track for the 65 ball bearing 10 and it will be seen that the anti-friction elements will permit the application and release of the brake beam without undue resistance due to the pressure of the beam on its support. The engagement of up- 70 wardly and downwardly facing surfaces on the support arm prevents the beam from tilting thus tending to equalize the wear on the opposite ends of the brake shoes.

Another construction in which the same 75 results are obtained is illustrated in Figures 3 and 4 in which the support arm 14 is an angle iron riveted to the spring plank 15 and slotted as indicated at 16 to provide bearings for roller elements 17 which are mounted upon a depending bracket 18 in itself forming a brace between the compression and tension members 19 and 20, respectively, of the brake beam. Rollers 17 are shown as being mounted upon a stud 21, the rollers 80 being retained by a suitable washer 22 and cotter 23.

Another modification of my invention is 85 illustrated in Figures 5 and 6 in which the horizontal flange of an angle iron support 24 carries the brake beam through rollers 25 which are seated in suitable pockets in the beam brace or cross piece 26. In this structure the depending leg 27 on the cross piece extends under the horizontal flange on the 90 support arm and is not provided with any anti-friction elements. In many applications it may be found unnecessary to provide an anti-friction element between the under- 95 side of the support arm and the beam.

Figures 7 and 8 illustrate another construction similar to that shown in Figures 5 and 6 but in which there is an anti-friction member 28 provided beneath the horizontal flange 29 of the support arm 30. The roller 28 is carried by a horizontal stud 31 mounted on the depending leg 32 secured to a beam cross piece 33.

Each of the structures illustrated utilizes 10 spaced bearing for supporting the beam and one or more bearings for preventing the tilting of the beam; the structure shown in Figures 3 and 4 utilizing the same bearings for both purposes.

Obviously the details of my invention may 15 be modified in numerous ways besides the illustrated embodiments, and I contemplate the exclusive use of all such modifications as fall within the scope of my claims.

20 I claim:

1. In a brake beam and mounting of the hangerless type, a beam, a support arm, and anti-friction elements carrying said beam on said arm and engaging opposite sides of said 25 arm.

2. In a brake beam, a compression member, a tension member, a cross piece between said members, and anti-friction elements carried on said cross piece between said members in- 30 termediate the portions of said cross piece engaging said members and adapted to engage upwardly and downwardly facing surfaces of a support arm to carry the beam and prevent its tilting.

3. In a brake beam, a compression member, a tension member, a one-piece brace between said members having an integral depending leg, and horizontally disposed anti-friction elements mounted on said leg for engaging a 40 support arm.

4. In a brake beam, a compression member, a tension member, a one-piece brace between said members having an integral depending leg, and horizontally disposed anti-friction elements mounted on said leg, each adapted 45 to engage upwardly and downwardly facing surfaces on a support arm.

5. In a brake beam and mounting of the hangerless type, a support arm adapted to be 50 secured to a car part and to extend beneath the brake beam and provided with a longitudinal slot, a brake beam bracket having a depending leg, and horizontally disposed rollers mounted on said leg and seated in said 55 slot.

6. In combination, a brake beam support arm adapted to be secured to a car part, a brake beam including a compression member and a tension member, a cross piece between 60 said members, a vertical projection on said cross piece at the side of said arm, and rolling elements mounted on said projection to engage upwardly and downwardly facing surfaces on said arm.

65 7. In a brake beam, a compression member,

a tension member, a cross piece between said members, a depending bracket on said cross piece, and vertically spaced elements on said bracket between said members and adapted to engage upwardly and downwardly facing surfaces, respectively, on a support arm disposed horizontally and transversely of the beam.

8. In combination, a brake beam, a support arm having upwardly and downwardly facing surfaces, and a plurality of anti-friction elements on said beam arranged to contact with either of said surfaces.

9. In a brake beam, a compression member, a tension member, a cross piece between said members, and anti-friction elements carried of said cross piece intermediate the portions of said cross piece engaging said beam members and adapted to engage opposite sides of a support arm.

In testimony whereof I hereunto affix my signature this 2nd day of May, 1927.

CHARLES I. WALKER.
